BEVERAGE BOTTLE CASE

Richard M. Scharff, Clayton, Mo., assignor to
Gerber Plastic Company, St. Louis, Mo., a cor-
poration of Missouri

Application October 9, 1944, Serial No. 557,758

1 Claim. (Cl. 220—21)

1 This invention relates in general to certain new and useful improvements in beverage bottle cases.

The present invention has for its primary object the provision of a uniquely designed unitary beverage bottle case or container molded as an integral or unitary structure from suitable plastic material.

It is a further object of the present invention to provide a beverage bottle case or container which is extremely rugged and durable and is relatively light-weight and compact in size.

It is an additional object of the present invention to provide a beverage bottle case or container molded of plastic having an extremely high impact strength and so designed as to provide maximum structural strength against breakage due to accident or mishandling.

It is another object of the present invention to provide a unitary or "one-piece" beverage bottle case or container which is substantially waterproof and will, therefore, not swell or rot or otherwise deteriorate under conditions of actual use.

Numerous other objects, advantages and inherent functions of the present invention will become apparent as the same is more fully understood from the following description which, taken with the accompanying drawing, discloses a preferred form of the present invention.

In the drawings (one sheet)—

Fig. 1 is a perspective view of a beverage bottle case constructed in accordance with and embodying the present invention;

Fig. 2 is a top plan view of the beverage bottle case;

Fig. 3 is a longitudinal sectional view of the beverage bottle case taken along lines 3—3 of Fig. 2; and

Fig. 4 is an end elevational view of the beverage bottle case.

Referring now in more detail and by reference characters to the drawing, which illustrates preferred embodiment of the present invention, A designates a beverage bottle case constructed in accordance with and embodying my present invention, and comprising a unitary or "one piece" structure molded of plastic material. The case A unitarily comprises four rectangularly arranged endwise connected side walls 1, 1'; and end walls 2, 2', integrally connected along their lower margins by a bottom wall 3 and above the bottom wall 3 the container is provided with a plurality of longitudinal partitions 4 and transverse vertical partitions 5, all integrally connected to each other at their several points of intersec-

tion, as at a, and likewise integrally connected along the bottom margins to the upper face of the bottom wall 3 in the formation of a plurality of bottle receiving compartments or pockets p.

5 In the region of each partition-intersection a, the bottom wall 3 is provided with a circular aperture 6, which extends up through the bottom wall 3, and the partitions 4, 5, are likewise cut away or relieved, as at b, b', in the formation of a four-way opening 7 between each of the four pockets grouped around such intersection point a. The particular embodiment shown in the drawing is a twenty-four bottle case, therefore, there will be fifteen such apertures 6 in the bottom wall 3. In addition, an inverted recess 8 is preferably though not necessarily, driven up into the material forming each partition connection a during the molding process for saving material and improving the curing characteristics of the molded case or container.

Formed upon the outer faces of the end walls 2, 2', midway between the corners of the case A, and adjacent the upper margin thereof, are outwardly and downwardly curved handles 9, preferably each having a plurality of arcuate depressions 10 upon its inner face for conforming to the fingers of the person carrying the case A, and, at its midway, each handle is provided with a central web 11 which extends inwardly and becomes an integral continuation of the central longitudinal partitions 4. Preferably, though not necessarily, the end walls 2, 2' of the case A are cut away below the handles 9 in the formation of side wall apertures 13 which, in conjunction with the apertures 6 of the bottom wall 3, provide for complete and free drainage of any water which may tend to accumulate in the bottom of the case A. Also formed integrally upon the outer faces of the end walls 2, 2', adjacent the corners of the case A, are vertical ribs 14 which project outwardly from the outer face of the end walls 2, 2', for a distance slightly greater than the distance of outward projection of the handles 9 so as to act as abutment members and protect the handles 9 from being broken or damaged when the cases are stacked.

Formed upon the upper face of the bottom wall 3, concentric within each of the pockets p, is a circular upstanding bead 15 adapted to loosely engage the bottom of the bottles and steady them when in the case or container. It may be stated in this connection that the bead 15 may, if desired, be omitted, and if employed should be provided with a plurality of radial channels, as

at 16, to allow for drainage of any water which may accumulate therein.

The case or container A, designed as above described, may be molded in a single unitary operation from a suitable plastic mix containing long shredded fibrous material which results in a container having extremely high impact strength. It will also be apparent that beverage bottle containers, constructed in accordance with the present invention, are extremely light-weight and, therefore, can be much more easily handled by delivery men and other persons connected with the handling, sale and distribution of carbonated beverages. Beverage bottle cases, constructed in accordance with the present invention, will drain freely so that there will never be any water or moisture in the cases. Finally, by reason of the use of molded materials, the beverage bottle case is entirely waterproof and will not swell, rot or deteriorate, as will the conventional wooden cases, when continuously subjected to the damp, wet conditions ordinarily encountered in actual use.

It should be understood that changes and modi-

fications in the form, construction, arrangement, and combination of the several parts of beverage bottle cases may be made and substituted for those herein shown and described without departing from the nature and principle of my invention.

Having thus described my invention, what I claim and desire to secure by Letters Patent is:

10 A one-piece molded plastic beverage bottle case comprising four rigid side walls integrally connected at their ends and a rigid bottom wall integrally connected to the lower margins of the side walls, a plurality of cell-forming partitions integrally connected with the side and bottom 15 walls and integrally interconnected with each other, said partitions being cut away in the regions of interconnection therebetween in the provision of a four-way drainage aperture, and an aperture formed in and extending through the bottom wall beneath and communicating with each of said drainage apertures.

RICHARD M. SCHARFF.
